UNITED STATES PATENT OFFICE.

EDGAR C. WHITESITT, OF SAN BERNARDINO, CALIFORNIA, ASSIGNOR TO STICKNEY EXPANSION DRILL & MANUFACTURING COMPANY, OF COEUR D'ALENE, IDAHO, A CORPORATION OF IDAHO.

DRILL BIT.

Application filed May 27, 1925. Serial No. 33,303.

This invention relates to improvements in drill devices of the class more particularly employed in deep well operations, and has for one of its objects to simplify and improve 5 the construction and decrease the expense of manufacture.

Another object of this invention is to produce a device of this character with the cutter members alike and interchangeable, thereby facilitating the renewal of impaired 10 parts. A further object of the invention is the provision of a device of this character, wherein the cutting elements are so constructed as to prevent excessive spreading of 15 the cutting heads thereof, with relation to each other, whereby the bit will be of the closed or non-expansion type in its operation.

A still further object of the invention is 20 to provide a device of this character in which the parts are few in number, and can be produced by drop forging or by similar rapid and inexpensive operations.

With these and other objects in view the 25 invention consists in certain novel features of construction as hereinafter shown and described and then specifically pointed out in the claim, and in the drawings illustrative of the preferred embodiment of the invention:—

Figure 1 is a side elevation.

Figure 2 is a side elevation partly in section.

Figure 3 is a transverse section on the line 35 3—3 of Figure 1.

Figure 4 is a transverse section on the line 4—4 of Figure 1.

Figure 5 is a transverse section on the line 5—5 of Figure 1.

Figure 6 is an edge view from the inside of one of the cutter members.

Figure 7 is a side elevation of the cutter member shown in Figure 6.

Figure 8 is an edge view from the exterior 45 of the cutter member shown in Figure 6.

The improved device comprises a stock 10 adapted to be attached to a drill rod or cable and bifurcated to form cheeks 11 and 12 in spaced and parallel relation with portions of 50 the outer ends reversely bevelled as represented at 13 and the remaining portions at right angles to the longitudinal axis of the stock as shown at 14'.

At the juncture of the cheeks 11 and 12

or at the crotch formed by the bifurcation 55 and the stock 10, recesses are formed to provide reversely curved seats 14 and 15.

A relatively heavy pin 16 connects the cheeks 11 and 12 as shown.

Movably disposed between the cheeks are 60 the cutter elements of the improved device, and as they are precisely alike and therefore interchangeable, the description of one will suffice for both.

Each of the cutter elements comprises a 65 shank 17 rounded to bear respectively in the seats 14 and 15, and each laterally enlarged at the other end as at 18 to provide a cutting head with a bevelled cutting edge 19 and a transversely bevelled shoulder 20 coating 70 with the bevelled ends 13 and 14 of the jaw portions when the cutters are in operative position.

Each cutter element is also formed with a half bearing 23 and a half socket 24, the 75 half bearings overlapping and engaging face to face with the half bearing of one member engaging in the socket 24 of the other member, as represented in Figures 2 and 3, to prevent lateral displacement of the cutters. 80

By this means the cutter members are 85 swingingly coupled between the jaw portions.

Each cutter element is likewise formed with another recess 25 to engage the pin 16 85 from opposite sides, as shown in Figures 2 and 3.

Each cutter element is likewise provided with a transversely extending shoulder 26 90 inclined slightly from the vertical transverse median of the head 18 and positioned at one side of and in proximity to said transverse median to engage the confronting faces of the head of the cutter elements, and thus reduce the friction and consequent wearing 95 of the parts.

The ribs likewise interlock and limit the outward movement and prevent the cutter members from becoming separated during the operation.

The shanks 17 of the elements are so proportioned that they permit the head 18 on which the cutting edges 19 are formed to slightly expand to provide for drilling a hole slightly larger than the stock 10, to obviate any tendency of the latter to bind in the drilled hole. 105

The improved drill bit herein shown is

designed to be used in starting the hole in the rock, and continuing the drilling until the point is reached where an enlargement of the hole is required to receive the explosive charge. The improved nonexpansive drill herein shown is withdrawn and an expansive drill bit substituted therefor, for instance the expansive drill bit illustrated in Patent No. 1,450,053, March 27, 1923, to 10 enlarge the drilled hole, to receive the explosive charge, or for other purposes.

Thus provision is made for drilling a hole of only slightly greater diameter than the stock 10 at a materially reduced expense of 15 time and labor, until the point where the explosion is to take place, and then drilling the necessarily enlarged hole to receive the explosive.

A water passage indicated at 27, is formed 20 through the stock 10, and a half passage 28 is formed in the contiguous faces of the shanks 17 of the bits, half passages 29 in the contiguous faces of the knuckles 23, and an aperture 30 through the pin 16. The various 25 passages, half passages and the pin aperture are in alignment longitudinally of the de-

vice, and constitute a continuous conduit for water.

Having thus described my invention what I claim is:

In a drill of the character described, a stock bifurcated to provide a fork having reversely beveled terminals, a cross coupling pin mounted in the fork, the stock being recessed at the inner end of the fork to provide separate seats at such end, coacting cutter members formed with head portions engaging respectively in the seats and with outer cutting ends and lateral shoulders to be engaged by the beveled terminals of the fork, said jaws having half sockets to receive the coupling pin, and means for swingingly coupling said cutter members above the coupling pin, said stock, coupling pin and cutter members being provided with axially disposed aligning passages communicating with the space confronted by the lateral shoulders.

In testimony whereof, I affix my signature hereto.

EDGAR C. WHITESITT.
